UNITED STATES PATENT OFFICE

HANS MELIN, OF YOUNGSTOWN, OHIO, ASSIGNOR TO THE AETNA STANDARD ENGINEERING COMPANY, OF YOUNGSTOWN, OHIO, A CORPORATION OF OHIO

SHEET CONVEYING APPARATUS

Application filed October 13, 1931. Serial No. 568,576.

This invention relating as indicated to sheet conveying apparatus, is designed primarily for the purpose of conveying hot sheets at a rolling or like temperature in association with rolling mills and like apparatus.

As is well known to those familiar with the art, one chief objection to sheet conveying tables associated with rolling mills and designed for the purpose of conveying sheets to and from the rolls is that the sheets in the areas in which they contact with the table lose a considerable portion of the heat so that when the sheet or pack is subsequently passed through the rolls uneven elongations will result and further internal stresses will be set up in the resultant material.

When a conveyor table employing endless laterally spaced chains is utilized as the means for conveying the sheets or packs, the sheets or packs resting on the table will have spaced dark bands indicating the areas in which there has been a transfer of heat from the sheet or pack to the supporting means.

It is among the objects of my invention to provide a form of sheet supporting and conveying means which will have none of the above named undesirable characteristics. Other objects of my invention will appear as the description proceeds. To the accomplishment of the foregoing and related ends, said invention, then, consists of the means herein-after fully described and particularly pointed out in the claim.

The annexed drawing and the following description set forth in detail certain mechanism embodying the invention, such disclosed means constituting, however, but one of various mechanical forms in which the principle of the invention may be used.

In said annexed drawing:—

Fig. 1 is a side elevational view of a conveyor chain constructed in accordance with the principles comprising my invention; Fig. 2 is a transverse sectional view of the chain illustrated in Fig. 1 taken on a plane substantially indicated by the line 2—2; Fig. 3 is a fragmentary sectional view similar to Fig. 2, showing an alternative form of construction of a portion of the chain; and Figs. 4 and 5

are respectively fragmentary and elevational views of a further and possibly preferred form of construction of the apparatus authorizing my invention.

Referring now more specifically to the drawing and more especially to Figs. 1 and 2, it will be noted that the structure illustrated in these figures is a portion of an endless chain such as is commonly employed for the purpose of conveying heated metallic sheets or packs in sheet mill installation.

The chain proper consists of spaced side bars 1 which form one link and which are connected to spaced side bars 2, forming the adjacent link. The side bars, and accordingly the links, are oscillatably interconnected by means of pins such as 3. The pin 3 has a central portion 4 of enlarged diameter which serves as a means for spacing the side bars of the chain and also as a means for rotatably supporting a roller 5 which normally runs on a track 6 and thereby supports the chain.

The means comprising my invention which have been designed for the purpose of directly supporting and engaging the hot sheets to be conveyed, consists of washer members 6 formed of refractory or non-inflammable thermally non-conductive material or material which has a relatively low thermal conductivity. These washers, which may be formed of asbestos or like material, are preferably provided with a central bushing 7 which rotatably support the washers on the pins 3.

The side bars, rollers and plates supporting washers are maintained in assembled relation upon the pins by means of end washers 8 and pins 9 projecting through the pins 3 and maintaining the several elements in assembled relation on the pins 3.

As most clearly illustrated in Fig. 3, instead of forming substantially the entire sheets supporting washers 6 of suitable thermally non-conductive material, as illustrated in Fig. 2, I may prefer to form such washers with a metallic body supporting portion 10 upon which is mounted a tire 11 of suitably thermally non-conductive material which will engage the sheets to be conveyed by the chain. When the construction such as is illustrated in

Fig. 3 is employed, I am enabled to use a material of suitable thermal non-conductivity and which does not have the strength possessed by the asbestos washers 6. When the sheet engaging material is supported by a base such as 10, I am enabled to use diatomaceous earth and the like which may be mixed with a suitable binder such as sodium silicate and placed on the ring 9 while in a plastic state and dried.

In Figs. 4 and 5 is illustrated a further modification of the construction comprising my invention, which construction may, for some reasons, be the preferred form. As illustrated in these figures, the sheet supporting members 12 of the chain which are of suitable material having relatively low thermal conductivity, are extended so as to be oscillatably secured to adjacent cross pins of the chain. These members 12 of course extend upwardly from the chain sufficiently to keep the sheet or packs from coming in contact with the metal portion of the chain.

One particular advantage which this last described form of construction has over the previously described forms is that larger areas are available for the support of the sheet and further, there is no possibility of the sheet supporting means rotating and permitting relative movement between the sheet and the conveying chain. If an apparatus such as is disclosed in Figs. 1 to 3 is employed, however, the washers 6 and 10 may be keyed to the cross shafts of the chain in order to prevent rotation and consequent relative movement between the sheets or pack and such chain.

Regardless of the particular form of construction employed, such as the asbestos washer illustrated in Fig. 2 or the structure illustrated in Figs. 3 to 5, it will be noted that when a conveyor chain is provided with such means for supporting the heated sheets the flow of heat from the sheet to the chain will be reduced to a very minimum so that the black bands normally occurring in the sheets when supported on the chain will be eliminated.

It is believed that a further description of the principles comprising my invention will not be necessary for those familiar with the art, it being noted that materials other than those enumerated may be employed if they possess the necessary properties above specified.

Other modes of applying the principle of my invention may be employed instead of the one explained, change being made as regards the mechanism herein disclosed, provided the means stated by the following claim or the equivalent of such stated means be employed.

I therefore particularly point out and distinctly claim as my invention:

65 A supporting and conveying mechanism

for sheets comprising a chain having side bars and cross pins, and auxiliary side bars of low thermal conductivity extending above said first named side bars.

Signed by me this 10th day of October, 70
1931.

HANS MELIN.
